UNITED STATES PATENT OFFICE.

GUSTAVE O. DEGENER, OF BROOKLYN, NEW YORK, ASSIGNOR TO ROYAL TYPEWRITER COMPANY, INC., OF NEW YORK, N. Y., A CORPORATION OF NEW YORK.

TYPEWRITING MACHINE.

Application filed February 12, 1926. Serial No. 87,874.

This invention relates to a typewriting machine in which the type bars are moved to the printing point by means of individual springs. Latch mechanism is provided for holding each type bar in its rest position against the tension of said spring and the key lever need be depressed merely far enough to release this latch mechanism. The type bars are returned to their normal or rest position by means of power driven mechanism. The latch mechanism is so constructed that it will retain the type bar when returned after operation even if the key lever has not been released. Means is also provided for preventing the simultaneous depression of two or more key levers.

The power driven mechanism as herein disclosed comprises a shaft which is rotated by an electric motor. When the machine is not in use the electric motor is not running, but is started by the depression of the first key struck. If subsequent keys are struck within predetermined intervals, the motor will run constantly so long as writing is being performed. If at any time the writing ceases for such predetermined intervals, the circuit is automatically broken and the motor stops.

The invention also comprises various detail improvements in a machine of this character which will be pointed out hereinafter and covered by the appended claims.

In the drawings:

Figure 1 is a fore and aft section through a typewriting machine embodying the invention with parts shown in elevation.

Figure 2 is a rear view.

Figure 3 is a front view of the means for preventing a depression of more than one key at a time, with key levers in section and parts broken away.

Figure 4 is a diagrammatic view of the circuit including the motor and the automatic switch mechanism.

Figure 5 is a side elevation of a type action showing the type bar in its operated position.

Figure 6 is a similar view showing the operated type bar returned to rest position, but before the release of the key lever.

Figure 7 is a view of the key lever and latch mechanism with its relation to the type bar at the moment of depression of the key lever.

Figure 8 is an elevation of the switch

mechanism with parts in section and parts broken away.

Figure 9 is a side elevation of the switch mechanism.

Figure 10 is a section on the line 10—10 of Figure 8.

Figure 11 is a section on line 11—11 of Figure 8.

Figure 12 is a view similar to Figure 8 but showing the parts in a different position.

The construction comprising the invention may be applied to typewriting machines of widely differing character but is illustrated herein as applied to the usual Royal machine. There is disclosed a machine frame A, carriage B supporting the usual platen C and controlled in its usual step-by-step movement by escapement mechanism comprising a ratchet wheel D controlled by the usual escapement dogs E. All these parts as well as the various other instrumentalities of the machine may be of any usual or desired character.

Mounted in the frame A is a cross bar 1 which supports a shaft 2 on which are mounted a plurality of key levers 3 arranged in the usual banks and provided with finger keys 4. Each key lever has an upwardly extending arm 5 to which is pivoted at 6 two latch members 7 and 8. The latch member 7 is provided intermediate its ends with a bent over ear 9 and the latch member 8 is provided with a similar ear 10, said ears lying opposite the upper ends of the extension 5 of the key lever and normally in contact therewith. These latch members are drawn toward each other by a coil spring 11 fast at its ends to the two members. The type bar 12 is pivoted at 13 in the usual type bar segment or in any desired manner. The head 14 normally lies adjacent a type bar rest 15 and at times contacts therewith. Adjacent the head 14 of the type bar each bar is provided with a bent over ear 16 with which cooperates a hook 17 formed on the latch member 7 and a hook 18 formed on the latch member 8. As clearly shown in Fig. 5, these hooks lie in different planes, for a purpose hereinafter set forth.

The heel of each type bar is provided with a slot 19 having an enlarged portion 20 and fitting in said slot 19 is a pin 21 carried by a sub-lever 22 which is pivoted on a shaft 23 carried by the side frames of the machine. An adjustable link 24 is connected to 110

each sub-lever 22 and is pivoted at 25 to the upper end 26 of a bell crank lever pivoted on a shaft 27 carried by the side frame of the machine. The other arm 28 of the bell crank lever is provided with a plurality of holes 29 in one of which is located a spring 30 which is attached at its other end to a plate 31 carried by a rock shaft 32. This rock shaft is provided with a worm gear 33 10 with which meshes a worm 34 on a short shaft 35 mounted in a bracket 36 and provided with a thumb screw 37. By turning this thumb screw 37 the shaft 32 may be rotated in one direction or the other and thereby the springs 30 may be simultaneously 15 adjusted to give them the desired tension.

Each sub-lever 22 is provided with a forwardly extending arm 38 which is guided in 20 a comb guide 39 carried by the cross bar 1. Each key lever has a rearward extension 40 provided with a bent over end 40' which is adapted to ride on the upper surface 41 of the extension 38 when the type bar moves 25 to its printing position as clearly shown in Figure 5. This will prevent the return of the actuated key lever to normal position until the type bar has been moved a considerable distance toward its rest position 30 and since only one key lever can be depressed at a time it is obvious that a second key lever cannot be depressed until the type bar has moved toward its normal position far enough to avoid any interference with a sub- 35 sequentially actuated type bar.

Pivotedly carried by the arm 26 of each bell crank lever at 42 is a cam member 43. This cam member is adapted to be engaged when a type bar has been operated by a 40 constantly rotating shaft 44 driven by the motor G and operating as hereinafter set forth.

Carried by a cross bar 45 supported in the machine frame, are brackets 46 which support a transverse member 47 provided with 45 an opening 48 therein, in which are mounted a plurality of balls or rollers 49. As clearly shown in Fig. 3 the space in the opening 48 is merely sufficient to allow one key lever to be moved down between two adjacent balls 50 or rollers displacing the others to each side. While this key lever is in depressed position no other key lever can be depressed, since the balls cannot separate far enough 55 to allow its passage. Each key lever is provided with an extension 50 which passes down between the balls and this extension is also guided by a comb guide 51 attached to the block 45 above mentioned.

A plurality of springs 52 are supported 60 by a cross bar 27' as shown in Figure 1 and each cam member 43 is engaged by one of these springs 52 when in idle position in order to prevent overthrow of said cam member or accidental displacement thereof.

65 Each connecting link 24 is provided with

a projection 53 which is adapted to cooperate with a plate 54 supported from a rock shaft 55 carried by the frame and an arm projecting from this plate engages the dog rocker so that each time one of the links 70 53 is moved forward the escapement mechanism will be operated in the usual manner.

The driving shaft 44 is covered with a strip of composition fabric 56 spirally wrapped around the shaft and fastened at 75 each end. The shaft is also provided with a worm 57 which meshes with a worm gear 58 on a shaft 59 which supports the usual centrifugal governor 60. On this shaft may also be mounted a drum 61 for use with carriage return mechanism if desired.

Whenever a key 4 is depressed the upper extension 5 of the key lever will move the latch member 7 through its ear 9 and thereby release the hook 17 from the ear 16 of the type bar. The spring 30 will then rock the bell crank lever on its shaft 27, pushing forward the link 24 and turning the sub-lever 22 about its shaft 23. By means of the pin and slot connection the type bar will be positively moved to the full line position shown in Figure 5. At this time the cam 43 carried by the bell crank lever will come in contact with the power shaft 44 and prevent further forward movement of the link 95 24 and sub-lever 22. The enlarged portion 20 of the slot 19 will, however, permit the type bar to complete its printing movement by momentum, moving to the dotted line position of Figure 5. It is desirable to allow 100 this lost motion for various reasons, particularly since it obviates the necessity of constructing the parts with such exactness that the cam 43 and power shaft 44 shall engage each other at exactly the moment that the type bar has been moved to its printing position by the pin 21 acting in the slot 19. By enlarging the slot at its end and allowing the type bar to complete its movement by momentum there is no necessity for accurate adjustment of the pin and slot.

The power shaft 44 is either running or is started upon a depression of a key. As soon as the cam 43 engages the power shaft as shown in Figure 5, the rotation of the shaft 115 in the direction of the arrow will cause the cam to rotate in the direction shown by the arrow and since the distance from the periphery of the cam to its pivot point increases, continued rotation of the cam will 120 bring the parts to the position shown in Figure 6 and positively return the type bar to a position wherein the ear 16 will be engaged by one or other of the lugs 17 or 18. In the position of the parts shown in Figure 6 125 it is assumed that the key has not been released and in this case the depression of the key is holding the latch 17 out of position to engage the ear or lug 16. However, at this time the latch 18 will engage the lug 130

16 and hold the type bar against a second movement even though the key has not been released. If the key is now released the latch members 7 and 8 will both move slightly to the rear and the hook 18 will release the lug 16 on the type bar but at the same time the hook 17 will move into a position to engage the same. It is for this reason that the hooks 17 and 18 lie in different horizontal planes.

Each successive actuation of a key lever will result in the same sequence of movements. The force with which the type bar strikes the platen can be adjusted by adjusting the tension of the springs 30 as above described. Since the bell crank lever and cam member 43 are returned quickly at each time as the cam 43 is rotating, it is desirable to provide the spring brake members 52 which will engage the cam at this time and prevent overthrow thereof.

As above stated, the motor is normally at rest because the circuit is broken by an automatic switch mechanism but is started by a depression of the first key operated. If subsequent keys are depressed with the usual speed, or within predetermined intervals of about three seconds, in the construction illustrated the motor will run constantly and the power shaft 44 will have a regular movement controlled by the governor 60. If, however, the operation of the keys is suspended for an interval greater than that predetermined, the circuit will again be broken and the motor will stop. The mechanism by which this result is attained will now be described.

In a casing 62 is mounted a pivot stud 63 on which is pivoted a generally U-shaped member 64 having a short arm 65 and a long arm or lever 66. A spring 67 is coiled about the stud 63 and engages the member 64 at one end, while its other end is held against movement by engagement with a pin 68 carried by the casing. This spring tends at all times to move the member 64 from the position shown in Figure 8 to that shown in Figure 12. The lever 66 has an enlarged central portion provided with an opening 69 and passing through this opening is a stud 70 provided with a bushing upon which is rotatably mounted a worm gear 71. A lever 72 is pivoted at 73 in the casing and is normally held in rest position by a spring 74, one end of which engages such lever and the other end of which is fastened to the casing by a screw 75. This lever has a tooth or shoulder 76 which as shown in dotted lines in Figure 8, normally engages the lower end of the lever 66 and holds the parts in the Figure 8 position, preventing their movement to the Figure 12 position to which the spring 67 tends to move the same.

Mounted in the short arm 65 of the member 64 is an insulating block 77 to which is

fastened by screws 78 a long spring 80, one of said screws also serving as a binding post for one of the circuit wires 79. A short shaft 81 is provided with a worm 82 adapted to mesh with the worm gear 71 and this shaft has at one end a cross pin 83 engaging in a slot 84 in an enlargement 85 carried by the drive shaft 44. Obviously when the parts are in the Figure 8 position a rotation of the drive shaft will also rotate the shaft 75 81 and turn the worm gear 71 by means of the worm 82. The other end of shaft 81 passes through an opening 86 in the side of the casing and its reduced end 87 is supported in a lever 88 carried by a shaft 89 supported in a bracket 90. This lever 88 has a bent over arm 91 which overlies the lever 92 pivoted at 93 to the casing 62 and at its free end overlying the lever 72. The spring 94 attached at one end to the lever 88 and at its other end to a pin 95 carried by the casing 62, tends to hold the parts in the Figure 9 position. An arm 96 carried by the other end of the shaft 89 has a slot 97 in which fits a pin 98 carried by a link 99, the other end of which is attached to the plate 54 carried by the rock shaft 55.

It will be evident that each time the plate 54 is moved through engagement of a projection 53 on the link 24 the shaft 89 will be 95 rocked, moving the free end of the lever 88 downward in Figure 9 and also moving the lever 92 and the free end of the lever 72. The movement downward of the lever 88 will move downward that end of the shaft 100 81 and therefore move the worm 82 out of engagement with the worm gear 71, as shown in Figure 12. At the same time, the downward movement of the lever 72 against the tension of the spring 74 will move the hook 105 or detent portion 76 downward out of the path of the end of the lever 66, thereby allowing the spring 67 to move this lever as well as the spring 80 to the Figure 12 position.

Attached to a wall of the casing is a block 100 of insulating material, upon which rests the plate 101 which is thereby insulated from the casing. A binding screw 102 connects the other terminal 103 of the circuit to the plate 101. This plate has an upstanding member 104 on one side of which is a block 105 of insulating material. At one side of the plate 101 is an ear 106 to which is attached a bent spring 107, while the other side of the plate has a similar ear 109 to which is attached a spring 110. The free ends of these springs are positioned as clearly shown in Fig. 10 so that they lie on opposite sides of the member 104 and one spring 110 is in contact with the insulating member 105.

Attached to the levers 66 by pivot 111 is a member 112, the free end of which is normally forced against a pin 113 by means of a spring 114. This ratchet member has a 115

tooth or detent 115 which is adapted to be engaged by a pin 116 on the worm gear, as hereinafter described.

When the parts are in the Figure 8 position, the circuit is broken since the spring 80 is in contact with the insulating block 105, as shown in Figure 10, and the motor is at rest. When a key is depressed, the parts move to the Figure 12 position, as previously described. In this movement of the spring 80 toward the left in Figure 12, it first contacts with the spring 107, closing the circuit and starting the motor. A continued movement will bring the spring 80 to the position *a* of Figure 10. At this time the parts are in the Figure 12 position and the worm 82 is out of contact with the worm gear 71. As soon as the gear lever is released the springs 74 and 94 will return the parts to the Figure 20 9 position, bringing the worm 82 into mesh with the worm gear 71. Since the motor has now been started the power shaft 44 is rotating and constantly the shaft 81 will also rotate. This will turn the worm gear 71 in a counter clock-wise position looking at Figure 12 and during this movement the pin 116 will contact with the latch 115 on the lever 66 and move this lever together with the arm 65 and spring 80 toward the right in Figures 10 and 12. The end of the spring 80 will pass through the position *b* and to the position *c*, the circuit being closed during this time. When the member 64 has moved this far to the right, the pin 116 will slide 35 off the detent 115 and the spring 80 will move from the position *c* to the full line position of Figure 10, contacting with the insulating block and breaking the circuit. This complete operation in the embodiment 40 shown, will take about three seconds and if a subsequent key has not been pressed in that interval, the circuit will be broken and the motor will stop. It is obvious, however, that if a subsequent key is depressed before the 45 parts have completed this movement that the end of the shaft 81 will again be moved downward breaking the connection between the worm 82 and the worm gear 71 and allowing the member 64 including the lever 66 50 and the spring 80 to move once more to the Figure 12 position, again closing the circuit. If the keys are rapidly depressed the lever will remain practically in this position all of the time and the worm and worm gear will 55 not engage long enough to produce any appreciable movement of the spring toward the right in Figure 12.

It is obvious that the foregoing construction provides means whereby the type bar 60 may be moved to printing position by a spring, the tension of which and consequently the force of the blow, can be regulated. The type-bar can also be returned to normal position by power means and will be retained in this position even if the operated 65

key lever has not been released. Since it is impossible to depress more than one key lever at a time and since even if the first key lever is released a second cannot be depressed until the type bar has completed an appreciable portion of its return movement, it is obvious that there can be no interference between the type bars. The invention also provides mechanism for controlling the motor which comprises the power shaft and in such manner that if the typewriting machine is operated at any usual speed the motor will remain constantly running at a speed regulated by the governor. If, however, the operation of the machine is discontinued for any appreciable interval, the circuit will be automatically broken and the motor comes to rest. The same operation which breaks the circuit will, however, bring the parts to such position that a subsequent operation of a key will again bring about the closing of a circuit and the consequent starting of the motor.

It is obvious that very many detail changes can be made in the precise construction embodying the invention without in any way departing from the spirit thereof which is to be regarded as limited only by the scope of the appended claims.

I claim:

1. In a typewriting machine, the combination of a type bar, means constantly tending to move said type bar to printing position, means directly engaging said type bar to hold it against movement, means for releasing said engaging means, and power means for returning the type bar to rest position.

2. In a typewriting machine, the combination of a type bar, means constantly tending to move said type bar to printing position, means directly engaging said type bar to hold it against movement, means for releasing said engaging means, power means for returning the type bar to rest position, and a second, means operative to hold the type bar in said rest position until the engaging means returns to normal position.

3. In a typewriting machine, the combination of a type bar having a projection, means constantly tending to move said type bar to printing position, a detent engaging said projection to hold the bar against movement, means for releasing said detent, power means for returning the type bar to rest position, and a second detent to engage said projection so long as the first is held in inoperative position.

4. In a typewriting machine, the combination of a type bar having a projection, means constantly tending to move said type bar to printing position, a key lever, a detent on said key lever engaging said projection to hold the type bar against movement, means for releasing said detent by movement of

95

90

100

105

110

115

120

125

130

the key, and power means for returning the type bar to rest position.

5. In a typewriting machine, the combination of a type bar having a projection, means constantly tending to move said type bar to printing position, a key lever, a detent on said key lever engaging said projection to hold the type bar against movement, means for releasing said detent by movement of the key, power means for returning the type bar to rest position, and a second detent on said key lever adapted to engage said projection and hold the type bar in rest position until the first detent returns to operative position.

6. In a typewriting machine, the combination of a type bar, means constantly tending to move said type bar to printing position, a key lever, two detents pivoted thereon, one detent being adapted to hold the type bar when the key lever is in normal position, and the other when the key lever is in operated position.

7. In a typewriting machine, the combination of a type bar, means constantly tending to move said type bar to printing position, power means for returning the type bar to rest position, a key lever, two detents pivoted thereon, one detent being adapted to hold the type bar against movement when the key lever is in normal position and the other when the type bar has been returned before the key lever returns to normal position.

8. In a typewriting machine, the combination of a type bar, means constantly tending to move said type bar to printing position, and connections between said means and type bar including a pin and slot, said slot being wide at one end to permit the type bar to perform the latter part of its printing movement through momentum alone.

9. In a typewriting machine, the combination of a type bar, means constantly tending to move said type bar to printing position, and connections between said means and type bar including a sub-lever, a pin thereon, and a slot in the heel of the type bar, said slot being wide at one end to permit the type bar to perform the latter part of its printing movement through momentum alone.

10. In a typewriting machine, the combination of a type bar, means constantly tending to move said type bar to printing position, and connections between said means and type bar including a sub-lever having a pin and slot connection with the heel of the type bar, means for limiting the movement of the sub-lever, and the slot being wide at one end to permit the type bar to perform the latter part of its printing movement by momentum alone.

11. In a typewriting machine, the combination of a type bar, means constantly tending to move said type bar to printing

position, and connections between said means and type bar including a sub-lever having a lost motion connection with the heel of the type bar, means for limiting the movement of the sub-lever, and a comb 70 guide for the same.

12. In a typewriting machine, the combination of a type bar, means constantly tending to move said type bar to printing position, and connections between said means and said type bar including an intermediate member, a key lever, and cooperating means on said member and lever which prevent the return of the key lever to normal position while the intermediate member is in fully 80 operated position.

13. In a typewriting machine, the combination of type bars, means constantly tending to move said type bars to printing position, a plurality of key levers, means for preventing the depression of more than one key lever at a time, and means preventing the return of an actuated key lever until the connected type bar has partly returned toward normal position.

14. In a typewriting machine, the combination of a typebar, a spring constantly tending to move said type bar to printing position, and intermediate connections between said spring and type bar including a 95 sub-lever engaging the type bar, a bell crank lever to which said spring is connected, and a link connecting said sub-lever and bell crank lever.

15. In a typewriting machine, the combination of a type bar, a spring constantly tending to move said type bar to printing position, and intermediate connections between said spring and type bar including a 100 sub-lever engaging the type bar, a bell crank lever to which said spring is connected, a link connecting said sub-lever and bell crank lever, and means for limiting the movement of the bell crank lever.

16. In a typewriting machine, the combination of a type bar, a spring constantly tending to move said type bar to printing position, and intermediate connections between said spring and type bar including a 110 sub-lever having pin and slot connection with the type bar, a bell crank lever to which said spring is connected, and an adjustable link connecting said sublever and bell crank lever.

17. In a typewriting machine, the combination of a type bar, a spring constantly tending to move said type bar to printing position, and intermediate connections between said spring and type bar including a 120 sub-lever having pin and slot connection with the type bar, a bell crank lever to which said spring is connected, an adjustable link connecting said sub-lever and bell crank lever, and means for limiting the movement of the bell crank lever.

18. In a typewriting machine embodying type bars and means for moving said type bars to printing position, means for returning the type bars to rest position comprising a rotatable shaft, a motor for driving said shaft, and means for maintaining said motor in operation so long as the interval between the return of one type bar to normal and the operation of the next lies within a predetermined limit.
19. In a typewriting machine embodying type bars and means for moving said type bars to printing position, means for returning the type bars to rest position comprising a rotatable shaft, a motor for driving said shaft, means for maintaining said motor in operation so long as the interval between the return of one type bar to normal and the operation of the next lies within a predetermined limit, and means for stopping the motor when the interval exceeds said limit.
20. In a typewriting machine embodying type bars and means for moving said type bars to printing position; means for returning the type bars to rest position comprising a motor, means for starting said motor, and means for maintaining said motor in operation so long as the interval between the return of one type bar to normal and the operation of the next lies within a predetermined limit.
21. In a typewriting machine embodying type bars and means for moving said type bars to printing position; means for returning the type bars to rest position comprising a motor, means for starting said motor by the operation of a type bar, and means for maintaining said motor in operation so long as the interval between the return of one type bar to normal and the operation of the next lies within a predetermined limit.
22. In a typewriting machine embodying type bars and means for moving said type bars to printing position; means for returning the type bars to rest position comprising a motor, means for starting said motor by the operation of a type bar, means for maintaining said motor in operation so long as the interval between the return of one type bar to normal and the operation of the next lies within a predetermined limit, and means for stopping said motor when the interval exceeds said limit.
23. In a typewriting machine embodying type bars and means for moving said bars to printing position; means for returning the type bars to rest position comprising an electric motor included in a normally open circuit, means for closing said circuit, and means for maintaining said circuit closed so long as the interval between the return of one type bar to normal and the operation of the next lies within a predetermined limit.
24. In a typewriting machine embodying type bars and means for moving said bars to printing position; means for returning the type bars to rest position comprising an electric motor included in a normally open circuit, means for closing said circuit by the operation of a type bar, and means for maintaining said circuit closed so long as the interval between the return of one type bar to normal and the operation of the next lies within a predetermined limit.
25. In a typewriting machine embodying type bars and means for moving said bars to printing position; means for returning the type bars to rest position comprising an electric motor included in a normally open circuit, means for closing said circuit by the operation of a type bar, means for maintaining said circuit closed so long as the interval between the return of one type bar to normal and the operation of the next lies within a predetermined limit, and means for stopping said motor when the interval exceeds said limit.
26. In a typewriting machine embodying type bars, means for moving said bars to printing position, escapement mechanism and a universal bar for operating the same; means for returning the type bars to rest position comprising a motor and means for starting said motor by movement of the universal bar.
27. In a typewriting machine embodying type bars, means for moving said bars to printing position, escapement mechanism and a universal bar for operating the same; means for returning the type bars to rest position comprising an electric motor included in a normally open circuit and means for closing said circuit operated by movement of the universal bar.
28. In a typewriting machine, the combination of a type bar, means for moving said type bar to printing position, and connections between said means and type bar including a pin and slot, said pin and slot having close engagement during the greater part of the movement of the type bar, but the slot being wider at one end to permit the type bar to perform the latter part of its printing movement through momentum alone.
- In testimony whereof, I have hereunto subscribed my name.

GUSTAVE O. DEGENER.
